UNITED STATES PATENT OFFICE.

WILLIAM H. HULINGS, OF MENLO PARK, CALIFORNIA.

HORSESHOE.

SPECIFICATION forming part of Letters Patent No. 228,533, dated June 8, 1880.

Application filed October 17, 1879.

To all whom it may concern:

Be it known that I, WM. H. HULINGS, of Menlo Park, county of San Mateo, State of California, have invented certain new and useful Improvements in Horseshoes; and I hereby declare the following to be a full, clear, and exact description thereof.

The invention consists in the combination of devices, as hereinafter described and claimed.

10 Figure 1 is a view of a shoe with a toe-weight attached. Fig. 2 shows the toe-weight detached and the removable piece for filling the socket in the shoe.

15 In the said drawings, C is a shoe having a weight, A, attached by means of a dovetailed shank, B, fitting in a correspondingly-shaped slot, a, in the shoe, and secured by a screw. When this weight is removed the shoe becomes a plain ordinary shoe, with no projections or 20 additions to interfere with the horse's action.

In order to render the shoe a perfect one, I form a small piece, m, which fits in the slot a, and is held by a screw, thus preventing dirt from entering the groove, so that the horse may be driven without the shoe showing any 25 sign of a toe-weight.

Having thus described my invention, I claim as new and desire to secure by Letters Patent—

20 The shoe C, having the dovetailed slot a, 30 jointly with the interchangeable piece m and toe-weight A B, as set forth.

In witness whereof I have hereunto set my hand.

W. H. HULINGS.
